CIRCUIT BREAKER

William J. Weinfurt, Wauwatosa, Wis., assignor
to McGraw Electric Company, Milwaukee, Wis.,
a corporation of Delaware

Application November 2, 1951, Serial No. 254,609

4 Claims. (Cl. 317—11)

1 This invention relates to circuit interrupters and is particularly directed to a circuit interrupter in which the combined action of an overload responsive circuit interrupter and electron discharge devices, such as those normally known as ignitrons, are employed.

Objects of this invention are to provide a circuit interrupter in which separable contacts are so associated with ignitrons that at the initiation of the opening motion of the separable contacts the ignitrons are caused to operate, with the ignitrons bridged directly across the contacts so as to provide means for shunting the current during the time that the contacts are opening with the ignitrons so arranged that ignition is discontinued at the proper time so that the current ceases to flow at the first current zero.

A specific feature of the invention is to provide means associated with the contacts for utilizing the voltage drop across resistors through which the main current passes for igniting the ignitrons during the initial portion of the opening stroke of the separable contacts.

Further objects are to provide a circuit interrupter in which the contacts are arranged to open at an extremely rapid rate, which is preferably though not necessarily in less than a half cycle, and in which the ignitor circuit of one or the other of the ignitrons immediately becomes effective at the initiating of the opening stroke of the contacts so that the proper ignitron depending on the direction of current flow, will come into operation to provide a low resistance shunt path across the contacts.

An embodiment of the invention is shown in the accompanying drawings in which:

The single figure is a diagrammatic view of the circuit interrupter.

Referring to the drawings, it will be seen that the circuit interrupter comprises a pair of movable contacts 1 and 2 which are pivotally mounted as indicated at 3 and 4 respectively, and are electrically connected by means of the conductor 5. These movable contacts 1 and 2 are each provided with contact making portions 6 and 7 which normally rest upon the main stationary contacts 8 and 9 as shown in full lines in the drawings. Auxiliary stationary contacts 10 and 11 are provided and are adapted to be engaged by the contact portions 6 and 7 of the movable contacts 1 and 2 respectively, while the contact portions are in engagement with the main stationary contacts 8 and 9. Further, the auxiliary contacts 10 and 11 are so arranged that they will remain in engagement with the contact portions 6 and 7 of the movable

2 contacts during the initial portion of the opening stroke of the movable contacts.

It is to be understood that the movable contacts 1 and 2 are connected by means of the connecting portion 12 which is pivotally connected to the movable contacts so as to cause the movable contacts to move in unison. The movable contacts are energized by means of an over center spring 13 connected to one of the contacts and to a rock arm 14. This rock arm is adapted to be moved from the full line position shown in the figure to the dotted line position so as to move the spring 13 across dead center. The contacts are designed to open preferably though not necessarily within less than a half a cycle under the influence of the spring 13.

The rock arm 14 is adapted to be operated by means of a magnetic plunger 15 which is drawn into a solenoid 16 when an overload current exists. 20 The arm 14 and the plunger 15 may be connected by means of the link 17. A spring 18 is provided for biasing the contacts towards closed position.

No attempt has been made to indicate the insulating portions of the apparatus but it is to be understood that the movable and stationary contacts are insulated from portions of the apparatus. Also it is to be understood that any suitable type of overload responsive means can be employed for actuating the movable contacts. 30 Further it is to be understood that any type of either single shot or repeating circuit interrupter or delayed action circuit interrupter can be employed as desired.

The terminals 19 and 20 are adapted to be connected in the line so as to place the circuit interrupter in series in the line. A pair of ignitrons indicated at 21 and 22 are connected "back to back" as will be seen as the description proceeds. The solenoid 16 of the circuit interrupter is connected directly to the terminal 20 on one side and to both the plate 23 of the ignitron 21 and the cathode 24 of the ignitron 22. The plate 25 of the ignitron 22 and the cathode 26 of the ignitron 21 are connected to the terminal 19. It is to be understood that the cathodes 24 and 26 of the ignitrons may be pools of mercury or other suitable metal in accordance with the usual practice. The ignitors of the ignitrons 21 and 22 are respectively indicated by the reference characters 45 27 and 28.

It is to be noted that the terminal 19 is connected to the main stationary contact 8 and the main stationary contact 9 is connected to the inner side of the solenoid 16 so that normally 55 the load current passes from terminal to terminal

through the stationary contacts 8, the conductor 5, the stationary contact 9, and the solenoid 16. However, upon the first portion of the opening stroke of the movable contacts 1 and 2 the main current is deflected through resistors 29 and 30 which are so arranged as to provide a voltage between the ignitors and the cathodes 27, 26, and 28, 24, of the ignitrons 21 and 22. The ignitrons as stated, are reversely connected. It will be noted therefore that one or the other of the ignitrons operates depending on the direction of current flow so that one or the other of the ignitrons always provides a low resistance shunt path across the contacts when the contacts start to open.

It will be seen that continued motion of the movable contacts 1 and 2 to their final dotted line position will cause complete deenergization of the ignitor circuits of both ignitrons so that the ignitrons will cease to function and the current flow will thereby be interrupted.

However, during the time that the first portion of the motion of the movable contacts 1 and 2 occurs, the proper ignitor will immediately come into operation to provide a bypass directly across the contacts thereby providing a low resistance current path between the inner end of the solenoid 16 and the terminal 19 thus preventing arcing at the contacts. Upon further opening motion of the contacts, it will be seen that the auxiliary contacts 10 and 11 are disconnected from the movable contacts 1 and 2 and consequently the ignitrons will be rendered nonconductive.

The full lines showing of the movable contacts is in their closed position, the movable contacts however have been shown in dotted lines at their final open position and in a partially open position.

It will be seen that a very simple type of circuit interrupter has been provided in which ignitrons are bridged across the separable contacts and are so arranged that one or the other immediately comes into operation during the initial portion of the opening stroke of the circuit interrupter.

Further it will be seen that the above results are accomplished without the expensive equipment and without the use of any auxiliary equipment whatsoever as the voltage drop across resistors is employed for energizing the ignitor circuit.

It is to be noted that the ignitrons are preferably so designed as to have short time high current carrying capacity and high inverse peak voltage characteristics.

Although this invention has been described in considerable detail, it is to be understood that such description is intended as illustrative rather than limiting, as the invention may be variously embodied and is to be interpreted as claimed.

I claim:

1. A circuit interrupter comprising switch means arranged for connection in a load circuit, overload responsive means for operating said switch means, a pair of ignitrons connected in a reverse manner across said switch means and including ignitors, and normally inactive auxiliary circuits including resistors bridged across the ignitor and cathode of the respective ignitrons and arranged to produce a voltage drop when

placed in the load circuit, said switch means including means for placing said resistors in the load circuit when said switch means is partially opened.

2. A circuit interrupter comprising switch means, overload responsive means for operating said switch means, a pair of ignitrons each including an anode, a cathode and an ignitor, said ignitrons being connected in a reverse manner across said switch means, a resistor for each igniton connected in shunt between the cathode and ignitor of the respective igniton, said switch means being connected in the load circuit of said circuit interrupter and including contact means normally shorting said resistors when said switch means is closed and auxiliary contact means for placing said resistors in said load circuit when said switch means is partially opened, whereby the load current will pass through said resistors for a brief period during the initial portion of the opening motion of said switch means.

3. A circuit interrupter comprising switch means, overload responsive means for operating said switch means, a pair of ignitrons each including an anode, a cathode and ignitor, said switch means including a pair of stationary main contacts and a pair of stationary auxiliary contacts arranged adjacent said main contacts and a pair of electrically connected movable contacts each normally in engagement with a main contact and an auxiliary contact, said auxiliary contacts being arranged to remain in engagement with said movable contacts for an instant after said movable contacts have left said main contacts during the initial portion of the opening stroke of said movable contacts, said ignitrons being connected in a reverse manner across said switch means, and a resistor for each igniton bridging the ignitor and the cathode and connected between the main and the auxiliary contacts.

4. A repeating circuit interrupter comprising switch means, overload responsive means for operating said switch means, a pair of ignitrons each including an anode, a cathode and ignitor, said switch means including a pair of stationary main contacts and a pair of stationary auxiliary contacts arranged adjacent said main contacts and a pair of electrically connected movable contacts each normally in engagement with a main contact and an auxiliary contact, said auxiliary contacts being arranged to remain in engagement with said movable contacts for an instant after said movable contacts have left said main contacts during the initial portion of the opening stroke of said movable contacts, said ignitrons being connected in a reverse manner across said switch means, a resistor for each igniton bridging the ignitor and the cathode and connected between the main and the auxiliary contacts, and means biasing said movable contacts towards closed position.

WILLIAM J. WEINFURT.
